ELECTROMECHANICAL STOP MOTION FOR
LOOMS

George F. Bahan, Charlotte, N. C.

Application August 21, 1939, Serial No. 291,234

7 Claims. (Cl. 139—355)

This invention relates to an electro-mechanical stop motion for looms and more especially to a stop motion of this type which is associated with the heddles through which the warp ends pass. These heddles are mounted in loom harnesses which are reciprocated up and down to form sheds through which the shuttle is adapted to pass when the cloth is woven.

In the present invention, each loom harness, when down, is disposed in an electrical circuit, but this circuit is not closed until a warp becomes broken, or slack enough to allow its associated heddle to drop. Upon the dropping of a heddle and the closing of a circuit, a magnet is energized which, in turn, actuates a suitable mechanism to stop the loom.

Heretofore, devices of this type have been made to perform the above-named result, such as shown in my Patent No. 1,999,623 of April 30th, 1935, but great difficulty has been encountered due to warp vibration or to loose ends in the warp which allowed the heddles to drop and make unnecessary electrical contacts. When these contacts were made the loom would stop unnecessarily, thereby necessitating the operator hunting for broken ends which did not exist.

It is, therefore, an object of this invention to provide an electro-mechanical stop motion controlled by the heddles in the loom harnesses, in combination with a stabilizing rod for engaging the lowermost shed of the warp so that objectionable vibration of the ends will be eliminated and so that the heddles through which these ends pass will be held upwardly out of electrical contact except when an end becomes broken. Also the slack warp ends and their associated heddles will be held upwardly to prevent an unwarranted electrical contact from being made.

It is another object of this invention to provide an electro-mechanical stop motion of the class described in combination with a resiliently mounted roller for supporting the lowermost shed and for holding the heddles in the shed out of electrical contact. This resiliently mounted roller prevents chafing when the yarn strikes the same and also allows the roller to yield to the lower warp shed as it pressed downwardly thereagainst.

By providing this combination, it is possible to eliminate the conventional stop motion drop wires thereby eliminating considerable friction in the warp. Another important result in the elimination of the conventional drop wires is the simplification of the drawing in process when a new warp is installed in the loom. From actual

experience and tests carried out upon the present invention, it has been found that there is less fly, less warp breaks per loom per day, less seconds, increased production, reduced costs, less loom parts to take care of, better face on the fabric, greater leverage on yarns, and a quicker stop upon the breakage of a warp end.

Some of the objects of the invention having been stated, other objects will appear as the description proceeds when taken in connection with the accompanying drawings, in which—

Figure 1 is a side elevation of portions of a loom showing certain portions thereof in section with my improved stop motion associated therewith;

Figure 2 is a sectional view taken along the line 2—2 in Figure 1 showing a heddle frame and warp stabilizing means with the central portions thereof broken away;

Figure 3 is a vertical sectional view taken along the line 3—3 in Figure 2;

Figure 4 is a sectional view similar to a portion of Figure 3 but showing the position of a heddle upon the breakage of its associated warp end.

Figure 5 is a sectional view showing a slightly modified form of the invention in which a roller is employed for stabilizing the lowermost shed instead of a bar;

Figure 6 is a sectional view taken along the line 6—6 in Figure 5.

Referring more specifically to the drawings, the numeral 10 denotes the side frames of a loom in which is mounted for oscillation a rocker shaft 11, said rocker shaft having fixedly secured thereon upwardly extending swords 12. The swords 12 support a lay 14 on the upper ends thereof and this lay has a suitable reed 16 therein, through which warp sheds 17 and 18 pass. The warp sheds 17 and 18 are drawn from a suitable letoff beam 19 which is rotatably mounted between the side frames 10. The warp sheds 17 and 18 pass from this beam over rod 20, roller 21, and through heddles 22 and 23 of heddle frames 24 and 25 respectively. During the normal operation of the loom the sheds 17 and 18 are reciprocated up and down by means of harnesses 24 and 25, respectively. Simultaneously with this reciprocation the lay 14 is oscillated back and forth so that a shuttle, not shown, can be thrown between the sheds to insert filling therethrough and form cloth.

The harnesses 24 and 25, are identical, therefore, one harness will be described and like reference characters given to the other. A plurality of additional harnesses may be used as desired.

By referring to Figure 2 it is seen that the harness 24 has top and bottom rails 26 and 27 respectively, which rails are joined together at their ends by metallic pipes 28 and 29. The top rail 26 supports a heddle bar 30, which bar, in turn, is adapted to have the upper end of heddles 22 mounted therearound. The upper end of the heddle 22 has an elongated slot 22a therein through which the heddle bar 30 is inserted. Lower rail 27 supports a similar heddle bar 32 which passes through suitable elongated slots 22b in the lower ends of heddles 22, said heddles 22 having holes 22c therein through which the warp ends forming the shed 17 are drawn. When the shed 17 is in lowermost position, as shown in Figure 3, the ends tend to raise the heddle 22 upwardly so that the heddle bars 30 and 32 will rest in the lower portions of slots 22a and 22b. In the frame 25, the heddles 23 have similar slots 23a and 23b fitting over heddle bars 30 and 32, and the central portion of each heddle 23 has a hole 23c therein through which ends forming the shed 18 are adapted to pass.

A contact bar 35 is supported by the lower rail 27, the upper side of said bar being disposed a slight distance below the heddle bar 32. This contact bar has a metallic wire 36 leading therefrom downwardly through the rail 27, said wire terminating in a metallic plate 37 on the lower side of the rail. When the harnesses are in lowermost position as shown in Figures 2 and 3, the lower ends of the associated heddles are disposed a slight distance above the contact bar 35, thereby leaving a space therebetween. This gap between the lower end of the heddles and the upper side of the contact bar 35 constitutes a switch and when these heddles are allowed to contact this bar with a harness in lowermost position, the switch is closed, allowing the current to actuate a suitable stopping mechanism on the loom. The parts 35, 36, and 37 constitute a portion of the circuit on one side of the switch. A portion of the circuit on the other side of the switch comprises the heddles 22 or 23, heddle bars 30 and 32, and end pipes 28 and 29, all of said members being made of a suitable conductive material. The end pipe 29 has a vertically disposed rod 40 slidably mounted therein. The upper end of this rod has nuts 41 threadably secured thereon and its lower end has an enlarged head portion 42 which serves to confine a suitable compression spring 43 around the rod 40 at a location between this head portion and the lowermost rail 27. This head portion 42 also serves to contact an inclined metallic plate 45 which is secured to the upper side of a suitable insulating block 46, said block being secured to a stand 47 and being shown in the form of a wooden block. It is secured in position by any suitable means such as bolts 48. A wire 50 is secured to the contact plate 45 as at 51, said wire having its other end connected to one side of a magnet 53. This magnet has a wire 54 leading from the other side thereof which wire is also secured to a terminal 55 of a suitable source of power such as storage battery 56. A bar 57 leads from the other side of battery 56, one end of said bar being connected to terminal 58 of the battery and its other end grounded as at 59 to the loom frame. When a harness is in lowermost position it is seen that the current can flow from the battery 56 through wire 54, magnet 53, wire 50, bar 45, head portion 42, wire 49, end piece 29, heddle bars 30 and 32, and heddles 22. If an end in the warp sheds 17 happens

to break in the manner as shown in Figure 4 then the associated heddle 22 will be allowed to drop to close the circuit and allow the current to also flow through bar 35, wire 36 and plate 37. From the plate 37 the current will pass through 5 a bar 60 which is secured to the upper side of a wooden block 61. This wooden block has suitable bolts 62 extending downwardly therefrom, and these bolts slidably penetrate the upper portion of stand 47. A compression spring 63 is disposed around each bolt 62 between the block 61 and the stand 47 so that when a harness 22 or 23 moves downwardly against the contact plate 60, there will be a yielding action on the part of the block 61. Nuts 65 are threadably secured on the lower ends of bolts 62 for adjusting the amount of compression in the spring 63 as well as for adjusting the height of the bar 60. The spring 43 (Figures 1 and 2) which is disposed between the head portion 42 and the lower rail 27 is provided for a similar reason, that is, it allows a yielding action to take place between the conductive bar 45 and the harness when said harness moves downwardly to make contact with the contact bars. 25

A wire 70 leads from the conductive bar 60 as at 69 said wire having its other end secured to the loom frame as at 71. Should an end break in the manner shown in Figure 4, a heddle 22 or 23 would be allowed to drop downwardly upon the contact bar 35. Then when the harness moves to lowermost position as shown in Figures 2 and 4, the previously described circuit is closed at the three essential points, namely, between the heddle bars 22 or 23 and the contact bar 35, between the conductive bar 60 and the plate 37 on the bottom portion of rail 27 and between the head portion 42 and the conductive plate 45. This will allow the current to flow from the source of power 56 to energize the magnet 53 40 and to cause the stop motion mechanism herein-after to be described to be operated. 35

A soft iron lever (Figure 1) 75 is pivoted intermediate its ends as at 76 said lever having the right hand end thereof normally disposed a slight distance above the end of magnet 53. The left-hand end of this lever has a vertically disposed link 77 connected thereto, the upper end of which is secured to the horizontal leg of a bell crank 78. This bell crank is pivoted as at 79 50 and its vertical leg is adapted to fit under the left-hand end of an inverted T-shaped member 80. This lever is pivoted as at 81 and has a suitable spring 82 disposed beneath its other horizontal leg. Also disposed in this other horizontal leg and above the spring 82 is a set screw 83, the upper end of which supports the free end of a lever 85. Lever 85 is pivoted as at 86 to the lower leg of knock-off lever 87 said knock-off lever being pivoted as at 88 to the loom frame 60 10. The lay 14 has a dog 89 secured to the lower side thereof. The end of this dog projects laterally and has a V-shaped notch 90 in the end thereof which fits the pointed end of lever 85 when the two parts come into contact with each 65 other. In normal operation, this V-shaped notch does not contact the free end of lever 85, but when the magnet 53 is energized, due to the breaking of an end, and the falling of a heddle 22 or 23, the right hand end of lever 75 is rotated 70 in a clockwise manner (Figure 1) to cause the link 77 to move upwardly and also to cause the bell crank 78 to rotate in a counter-clockwise manner. This rotation will allow the upper end of the vertical leg of the bell crank to move into 75

notch 80a in the lower side of the lever 80, and thereby allow a slight counterclockwise rotation of this lever due to the upward pressure exerted by compression spring 82. When this is done the 5 set screw 83 will be moved upwardly to also push the free end of lever 85 upwardly so that it will be disposed in the path of dog 89. When the free end of the lever 85 is in this position and upon the next oscillation of the lay of the loom, 10 the dog 89 will engage this lever thereby rotating the knock off lever 87 in a counter-clockwise direction about pivot 88, to actuate suitable mechanism, not shown, for stopping the loom. 15 A part of this loom stopping mechanism comprises shipper lever 91.

As heretofore stated, great difficulty has been encountered with vibrating warps, and in warps having slack ends therein, these slack ends will cause the circuit to be closed and the loom to be 20 stopped when there are no ends actually broken. In order to eliminate this false alarm feature, a suitable stabilizing rod 95 has been provided and this rod is disposed transversely of the warp ends directly below the sheds. The rod is positioned at such an elevation that the lowermost 25 shed will always be supported to cause the heddles 22 and 23 to be held upwardly out of contact with the contact bar 35 except when an end is broken. The ends of the stabilization rod 30 95 are slidably mounted around suitable bolts 96, said bolts being secured to horizontally disposed arms 97 extending from the side frames 10 of the loom. The members 97 have suitable holes 98 35 therein which are penetrated by bolts 99 to secure these members to the side frames of the loom. By providing the holes 98 an adjustment of the horizontal distance between the rod 95 and the harnesses can be made.

Disposed below the ends of stabilization rod 40 95 and around the bolts 96 is a compression spring 100 which normally urges the rod upwardly. Also disposed around these same bolts 96 and above the rod 95 is a second spring 101 which merely serves as a check to prevent the bar from 45 moving upwardly too far when the downward pressure of the lowermost shed is suddenly released. This added feature serves to stabilize the warp and prevent vibration of the individual ends, and also serves to give the necessary support to the slack ends to prevent their associated heddles from making a contact except when the ends are broken.

Figures 5 and 6 show a slightly modified form 50 of the invention in which the stabilization rod 95 is replaced by a roller 105. Each end of the roller 105 has a restricted portion 106 which rotatably penetrates a block 107 as well as slots 108 and 109 in opposed sides of a suitable pipe 110. A compression spring 111 is disposed below 55 the block 107, said spring being confined in the pipe by means of a plug 112 which is threadably secured in the lower end thereof. The upper side of the block 107 has a compression spring 114 resting thereon which acts as a check to prevent 60 the block 107 and the roller 105 from bouncing upwardly an objectionable amount upon the release of the warp pressure, during the operation of the loom. This spring 114 is confined within the pipe 110 by means of a suitable cotter 65 pin 115.

The pipe 110 is exteriorly threaded near its upper end. This pipe penetrates the outstanding leg of a suitable angle member 117, said angle member being secured to the side frame of the 70 loom 10 by means of bolt 118. Nuts 120 and 121

are threadably secured around the upper end of the pipe 110 above and below the outstanding leg of the angle 117, so that the pipe will be rigidly secured to the angle member. The rod or roller 75 105 functions substantially the same as the bar 95, except that the roller is subject to rotation. Therefore, when the shed engages this roller upon its downward motion, there will be no chafing of the yarn because the roller can adjust itself to the sliding action of the shed.

It is thus seen that when a heddle frame is lowered, the weight of the warp and the heddles carrying those threads having normal tension therein will move the rod 95 or 105 downwardly, 10 whereas the warp threads having sub-normal tension therein will not exert this effect, and thus will tend to equalize the position of all of the warp threads. This will support the subnormal warp threads and prevent the heddles carried thereby from closing the circuit. Also it is seen 15 that if the heddle frame is raised that the bar 95 or 105 will move upwardly, thus raising the subnormal warp threads and thus preventing these low-tensioned warp threads from being left 20 behind to close the circuit by the dropping of a heddle.

In the drawings and specification there has been set forth a preferred embodiment of the invention, and although specific terms have been 25 employed, they are used in a generic and descriptive sense only, and not for purposes of limitation, the scope of the invention being set forth in the appended claims.

I claim:

1. In a loom having a stop motion and a plurality of vertically reciprocating harness frames having vertically movable metallic heddles therein, normally held in elevated position by the tension of the warp in a loom when a harness frame is in lowered position, and upon the failure of being sustained by the warp, closing an electrical circuit by downward movement to operate the stop motion of the loom, a rod disposed transversely of and below the warp threads 40 and being disposed a substantial distance from the harness frames, resilient means engaging each end of the rod for movably supporting the same, said rod being engageable and movable downwardly by the warp upon the lowering of a harness frame to prevent heddles having loose 45 unbroken warp ends therein from closing said circuit.

2. A warp stop motion for looms comprising 50 a control circuit for setting in operation the stopping mechanism, a series of vertically reciprocating harness frames, terminals carried by each frame, means to include said terminals in the controlling circuit when a frame is in its lowered position, a series of metallic heddles in 55 each harness frame and normally maintained inoperative by their warp threads when the frame is down, breakage of a warp thread releasing its heddle and causing closure of the control circuit through the terminals in the frame 60 while said terminals are in circuit, a rod disposed transversely of and below the warp thread and being disposed a substantial distance from the harness frames, resilient means for supporting the ends of the rod, said rod being adapted 65 to be engaged by the warp threads and movable downwardly by the warp threads when a harness frame is lowered, for preventing unbroken warp threads having subnormal tension therein from allowing the heddles carried 70 by 75

said threads having subnormal tension therein from closing the circuit.

3. A warp stop motion for looms comprising a control circuit for setting in operation the warp stop motion, a plurality of harness frames each having a series of metallic heddles, terminals carried by the frames and adapted to be electrically connected by a heddle when released by parting or subnormal tension of its warp thread, contact terminals remote from the frames and engageable by the terminals carried by a frame when a harness frame is at or near its lowest position, a rod extending transversely of the loom and being disposed a substantial distance from the harness frame, resilient means for supporting the ends of the rod, said rod being adapted to be engaged by the warp threads and movable downwardly by the warp threads when a harness frame is lowered, for preventing unbroken warp ends having subnormal tension therein from allowing the heddles carried thereby to close said controlling circuit.
4. A warp stop motion for looms comprising a controlling circuit for setting in operation the stopping mechanism, a plurality of harness frames each having a series of metallic heddles, terminals carried by the frames and adapted to be electrically connected by a heddle when released by parting or subnormal tension of its warp thread, contact members on the outside of the frames and connected with said terminals, a pair of fixed contact members in the controlling circuit and adapted to be engaged by said contact members on the harness frames when a harness frame is in lowermost position, a rigid member, spring mounted means for supporting the ends of the rigid member, said rigid member being disposed transversely of the loom and being adapted to be engaged and moved downwardly by the normally tensioned lowermost warp threads supporting the heddles in a harness frame when the harness frame is in its lowest position, said rigid member serving to support the warp threads and prevent unbroken warp threads having subnormal tension therein from allowing the heddles carried thereby to move downwardly far enough to close said circuit.
5. In a loom having a stop motion mechanism and a plurality of harness frames mounted for vertical reciprocatory movement in the loom, a plurality of vertically movable metallic heddles

carried by each harness frame, an electric circuit for the stop motion means carried by the loom and heddle frames for completing an electric circuit to the stop motion by the falling of a heddle in a harness frame when unsupported by its warp end, a rod disposed transversely of the loom below the lowermost warp threads for engaging the warp threads in a lowered harness frame and supporting the same to prevent the heddles carried by unbroken warp threads having subnormal tension from falling downwardly sufficiently to close the stop motion circuit, and spring means for supporting the ends of the rod.

6. In a loom having a stop motion and a stop motion circuit, a plurality of vertically reciprocable harness frames having metallic heddles therein supported by the warp threads when the harness frames are moved to lowermost position, means carried by the loom and each harness frame for completing the stop motion circuit through said heddles when the heddle falls downwardly in its harness frame when unsupported by a warp thread, a bar extending transversely of the loom and below the warp threads for supporting the warp threads when a harness frame is moved to its lowermost position, to prevent the heddles carried by unbroken warp threads having subnormal tension therein from falling downwardly sufficiently to close the stop motion circuit, and spring means for supporting the ends of the bar.

7. In a loom having a stop motion mechanism adapted to be energized by the dropping of a heddle in a harness frame, a rod disposed transversely of the loom and below the warp and being a substantial distance from the harness frames, spring means for supporting the ends of the rod, said rod being adapted to be engaged by the warp in a lowered harness frame and to be moved downwardly by the weight of the warp and the heddles carried by the warp whereby the warp threads having normal tension therein will exert pressure for moving the rod downwardly and will thus equalize the position of the warp threads having subnormal tension therein and will thus prevent the heddles carried by the last-named warp threads from allowing the heddles carried thereby to lower a sufficient amount to close the stop motion circuit.

GEORGE F. BAHAN.
